[57] **CLAIM**

The ornamental design for a lighting fixture, as shown and described.

DESCRIPTION

FIG. 1 is a top, front, right side perspective view of a lighting fixture showing my design as embodied in a track light;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a top, front, right side perspective view of a second embodiment of my new design as embodied in a ceiling mounted light;

FIG. 7 is a bottom plan view thereof;

FIG. 8 is a front elevational view thereof;

FIG. 9 is a rear elevational view thereof; and,

FIG. 10 is a left side elevational view thereof.
